Patented Jan. 23, 1973

226,111

DICE AGITATOR

Milton Kahn, 142 Greene St., New York, N.Y. 10012

Filed June 21, 1971, Ser. No. 155,412

Term of patent 14 years

Int. Cl. D21—01

U.S. Cl. D34—5

Fig. 1.

Fig. 2.

Fig. 3.

FIG. 1 is a front perspective view of the dice agitator, embodying the features of my new design,

FIG. 2 is a rear elevation view, and

FIG. 3 is a top plan view thereof.

I claim:

The ornamental design for a dice agitator, substantially as shown and described.
